UNITED STATES PATENT OFFICE.

DANIEL M. HARRIS AND SEWINGTON S. BURNET, OF SALEM, MASSACHUSETTS.

IMPROVED CLOTHES-WRINGER.

Specification forming part of Letters Patent No. 35,234, dated May 13, 1862.

To all whom it may concern:

Be it known that we, DANIEL M. HARRIS and SEWINGTON S. BURNET, both of Salem, in the county of Essex and State of Massachusetts, have invented new and useful Improvements in Clothes-Wringers, of which the following is a full and exact description of the construction and operation of the same, reference being had to the annexed drawings, making a part of this specification, in which—

Similar letters refer to similar parts.

Figure 1 represents a side elevation. Fig. 2 represents an end elevation. Fig. 3 represents the form of the rings of which the rolls are made.

a a are the standards of the machine, which rest upon the rim of the tub, as shown at *a*, Fig. 2. These standards are held together by the brace *b*, which passes through each standard, and is fastened at each end by pins. In these standards *a a*, at *o* and *o'*, Fig. 2, are boxes, in which the bearings of rolls *c c'* revolve, *o'* being slotted vertically to allow the rolls to open or be brought closer together, as may be required, in passing through goods of different thickness. The rolls *c c'* are made of rings cut from vulcanized-rubber packing, in form as shown in Fig. 3, and slipped upon the shafts and cemented as they are put on.

We are aware that rubber rolls have been made and used for some time. Therefore we do not claim to be the inventors of rolls for this purpose, but of an improvement in putting the rubber on to insure adhesion to the shaft and to make them firmer and more elastic. As rolls are now used they are made of rubber tubing from seven to ten inches in

length and the iron shaft forced into them. Whatever substance is put on the shaft to make the roll adhere is scraped off by the rubber in forcing the shaft into it. This difficulty is overcome by making the rolls of the rings and cementing each piece as it is put on, thereby preventing the possibility of the roll turning upon the shaft and making the roll more firm and elastic.

The strap *e* clasps each end of the shaft of roll *c'*, and is kept in place by pins *f f*. The strap *e* is then connected with clutch *g* by a rod, *h*, which has a screw or thread cut on the lower end, to which is fitted a thumb-nut, *i*. The top of the clutch *g* projects out from the tub to allow the rubber spring *j* to work freely, the spring allowing the rolls *c c'* to accommodate themselves to any thickness of goods. Turning the thumb-nut *i* against the spring *j* serves the double purpose of fastening the machine to the tub and giving to the rolls any required pressure.

What we claim, and desire to secure by Letters Patent as our invention, is—

The combination and arrangement, in a clothes-wringer, of the strap *e*, attached to the ends of shaft of roll *c'*, working in the slotted boxes *o' o'*, the rod *h*, the thumb-nut *i*, rubber spring *j*, and clutch *g*, operating together in the manner described, for the purpose specified.

DANIEL M. HARRIS.
S. S. BURNET.
